UNITED STATES PATENT OFFICE.

MAX L. HILLMER AND LESLIE O. PARKER, OF ANDERSON, INDIANA, ASSIGNORS TO REMY ELECTRIC COMPANY, OF ANDERSON, INDIANA, A CORPORATION OF INDIANA.

ENGINE-STARTER GEARING.

Application filed June 28, 1921. Serial No. 481,142.

To all whom it may concern:

Be it known that we, MAX L. HILLMER and LESLIE O. PARKER, citizens of the United States of America, residing at Anderson, county of Madison, State of Indiana, have invented certain new and useful Improvements in Engine-Starte Gearing, of which the following is a full, clear, and exact description.

- 10 This invention relates to automatic gearing especially adapted for use with electric motors for starting internal combustion engines. It is generally well known that by means of such gearing when the motor is connected with a current source to crank the engine, the motor is automatically connected with the engine by virtue of the motion of the motor; and that when the engine becomes self operative the motor is automatically disconnected from the engine. Such automatic gearing usually includes a gear connected with the motor which is moved either endwise or laterally into engagement with the engine flywheel gear.
- 15 One object of the present invention is to improve automatic gearing of the type wherein a gear geared to and supported by the motor shaft is moved laterally into engagement with the engine gear.
- 20 Further objects and advantages of the present invention will be apparent from the following description, reference being had to the accompanying drawings, wherein a preferred embodiment of the present invention is clearly shown.

In the drawings:

Fig. 1 is a side elevation of gearing embodying the present invention;

Fig. 2 is a top view thereof;

40 Fig. 3 is an end view thereof showing the gearing disconnected from the engine;

Fig. 4 is a view similar to Fig. 3 showing the gearing connected to the engine; and

45 Fig. 5 is a sectional view taken on the line 5—5 of Fig. 3.

Referring to the drawings, 20 designates a fragment of a motor having an end frame 21 supporting motor shaft 22 carrying motor pinion 23 which meshes with idle

50 gear 24 adapted to mesh with engine flywheel gear 25 (a fragment being shown). Shaft 22 supports a bracket or yoke 26 having arms 27 provided with elongated holes 28 through which idle gear shaft 29 pro-

jects. Members 30 are spacing washers and 55 31 are cotter pins to secure the shaft 29 in position. Normally shaft 29 is pressed by thimbles 32 and springs 33 against the ends of elongated holes 28 remote from shaft 22.

Washer 34 bears against a shoulder 60 formed by reducing the end of shaft 22 said reduced end being threaded at 35 to receive nut 36 which secures the yoke 26 upon shaft 22.

A lug 37 extending from end frame 21 65 slidably supports a sleeve 38 having a flange 39 at one end. The opposite edge of sleeve 38 is cut and bent to form outwardly projecting stops 40 and inwardly projecting stops, one being shown at 41. A buffer 70 spring 42 is interposed between the lug 37 and the flange 39 of sleeve 38, and a flat surface 43 is provided on yoke 26 to strike against flange 39. A spring 44 is interposed 75 between the bottom of hole 45 in yoke 26 and the stops 41 of sleeve 38.

Normally the gearing is in the position shown in Fig. 3, the motor being at rest. To crank the engine current is supplied to the motor, and shaft 22 begins to turn, thereby 80 rocking the yoke 26 into the position shown in Fig. 4 before the inertia of rotation of gear 24 is entirely overcome and this gear begins to rotate. A dished spring washer 30^a may be used to increase the friction 85 between the yoke 26 and the motor pinion 23. The effect of this spring will be added to the inertia effect referred to. As the yoke 26 swings counterclockwise, taking up the motion of shaft 22, the gear 24 will center 90 itself with respect to the centers of pinion 23 and gear 25. As a tooth of gear 24 rolls into a tooth space of gear 25, an opposite tooth of gear 24 will roll farther into mesh with pinion 23. In case a tooth of gear 95 24 faces with a tooth of gear 25, this pressure is partially relieved by the sliding of gear 24 toward pinion 23, thereby permitting the facing tooth of gear 24 to slide off the face of a tooth of gear 25 and then permitting 100 this tooth to roll into mesh with gear 25 as if no interference had occurred.

The swinging of yoke 26 is yieldingly limited by buffer spring 42 as the surface 43 of yoke 26 strikes against flange 39 of sleeve 105 38. As shown in Fig. 4, spring 44 is compressed to occupy the space in sleeve 38 and in yoke 26.

When the engine becomes self operative and the linear speed of flywheel gear 24 tends to exceed that of gear 25 when driven by the motor, the direction of tooth pressure is reversed and the gear 25 is thrown by gear 24 out of mesh, and is restored to normal position. Spring 44 yieldingly maintains the gearing in normal position as shown in Fig. 3.

10 As an aid to the spring 44, a spring 48 connecting yoke 26 with frame 21 may be used (see Figs. 1 and 3). Or if desired, the spring 48 may be used instead of spring 44.

15 While the form of mechanism herein shown and described constitutes a preferred form of embodiment of the invention, it is to be understood that other forms might be adopted, all coming within the scope of the claims which follow.

20 What we claim is as follows:

1. In automatic gearing for engine starters, the combination with an engine spur gear, a motor having a shaft and a pinion carried by said shaft; of an idle spur gear 25 meshing with the pinion; and means for supporting said idle gear from said shaft and guiding said idle gear into mesh with said engine gear while permitting said idle gear to center itself with respect to said 30 pinion and said engine gear.

2. In automatic gearing for engine starters, the combination with an engine spur gear, a motor having a shaft and a pinion carried by said shaft; of an idle spur gear 35 meshing with the pinion; and a bracket swung upon said motor shaft for supporting said idle gear, said bracket having provisions for permitting the idle gear to center itself with respect to the pinion and the 40 engine gear.

3. In automatic gearing for engine starters, the combination with an engine spur gear, a motor having a shaft and a pinion carried by said shaft; of an idle spur 45 gear meshing with the pinion; a shaft carrying the idle gear; and a bracket swung upon said motor shaft and having provisions for supporting said idle gear shaft and permitting lateral movement of said idle gear 50 shaft, whereby said idle gear may center itself with respect to said pinion and said engine gear.

4. In automatic gearing for engine starters, the combination with an engine spur gear, a motor having a shaft and a pinion carried by said shaft; of an idle spur gear meshing with the pinion; a shaft carrying 55 said idle gear; and a bracket swung upon said motor shaft having arms provided with 60 elongated holes extending radially of said motor shaft, said idle gear shaft extending through said holes, whereby said idle gear

may center itself with respect to said pinion and said engine gear.

5. In automatic gearing for engine 65 starters, the combination with an engine spur gear, a motor having a shaft and a pinion carried by said shaft; of an idle spur gear meshing with the pinion; and means for supporting said idle gear from said 70 shaft and guiding said idle gear into mesh with said engine gear while permitting said idle gear to center itself with respect to said pinion and said engine gear; and means for yieldingly limiting the movement of said 75 first means.

6. In automatic gearing for engine starters, the combination with an engine spur gear, a motor having a shaft and a pinion carried by said shaft; of an idle spur gear 80 meshing with the pinion; and a bracket swung upon said motor shaft for supporting said idle gear, said bracket having provisions for permitting the idle gear to center itself with respect to the pinion and the 85 engine gear; and means for yieldingly limiting the movement of said bracket.

7. In automatic gearing for engine starters, the combination with an engine spur gear, a motor having a shaft and a pinion carried by said shaft; of an idle spur gear meshing with the pinion; a shaft carrying the idle gear; and a bracket swung upon said motor shaft and having provisions for supporting said idle gear shaft and permitting lateral movement of said idle gear shaft, whereby said idle gear may center itself with respect to said pinion and said engine gear; and a buffer spring arranged to be engaged by said bracket yieldingly to 100 limit the movement thereof.

8. In an automatic gearing for engine starters, the combination with an engine gear, a motor having a shaft and a pinion carried by said shaft; of an idle gear meshing with the pinion; an end frame for said motor carrying a lug; a bracket for supporting the idle gear on said shaft and for guiding the idle gear into mesh with the engine gear; a return spring supported by said lug for maintaining the idle gear out of mesh with the engine gear; a sleeve slidably mounted on said lug and surrounding the return spring; and a buffer spring mounted on said sleeve and adapted to be engaged by the bracket upon a predetermined movement thereof toward the engine gear.

In testimony whereof we hereto affix our signatures.

MAX L. HILLMER.
LESLIE O. PARKER.
